UNITED STATES PATENT OFFICE.

WELLS A. UNDERWOOD, OF WOOSTER, OHIO.

BOX-LOOP FOR HAME-TUGS.

SPECIFICATION forming part of Letters Patent No. 277,434, dated May 8, 1883.

Application filed January 18, 1883. (No model.)

To all whom it may concern:

Be it known that I, WELLS A. UNDERWOOD, a citizen of the United States, residing at Wooster, in the county of Wayne, in the State 5 of Ohio, have invented certain new and useful Improvements in Box-Loops for Hame-Tugs, of which the following is a specification.

My invention relates more particularly to those hame-tugs in which the box-loop is 10 adapted to be slid in between the two arms of the clip, and removable therefrom by the removal of a single attaching-rivet; but the loop is also adapted for use in any customary form of tug, and is so constructed as to be capable 15 of sewing or otherwise attaching to its position.

My improved loop is made of metal in box form, the sides being solid and connected above and below by metallic bars formed integrally 20 therewith. A loop thus made is stronger and more durable than a leather loop. Easy access is allowed through the top cross-bars to the strap, and easy attachment to the tug, if necessary, by the looping of the thread over the 25 bottom cross-bars.

In the drawings, Figure 1 represents in section the metallic loop applied to a hame-tug, such as shown in Patent No. 260,905, of T. A. Simmons. Fig. 2 is a perspective view of the 30 loop.

My improved box-loop is made with solid metal sides *a*, connected by metallic cross-bars *b* at bottom and *c* at top. The sides *a* are cut away between the bars *c c*, thus allowing ready access to the strap and easy manipulation thereof. It will be seen that the loop, although adapted to be employed, as illustrated in Fig. 35 1, in a tug in which the loop is inserted by slipping it between the arms of the clip and then all parts fixed together by a single rivet, is 40 also adapted for use in those tugs in which the loop is attached by means of sewing. In such tugs the thread connecting the loop will be passed over the bars *b*, by which means the loop will be held securely in place. 45

Having thus described my invention, what I claim as new, and desire to secure by Letters Patent, is—

The metallic box-loop for hame-tugs, consisting of sides *a a*, being cut away, for the purpose described, and united at the top by cross-bars *c c c* and at the bottom by cross-bars *b b b*, as and for the purposes set forth. 50

WELLS A. UNDERWOOD.
